INSTRUMENT FOR DRAWING NONCIRCULAR CURVES

Philip Blampied, Flushing, N. Y.

Application June 25, 1947, Serial No. 756,888

2 Claims. (Cl. 33—27)

1

My invention is an improvement belonging to the class of instruments for making curved lines on paper and the like, in the laying out of drawings and pictorial designs; and particularly an implement for producing arcs and curves of any desired configuration, with a single continuous motion of the part that carries the marking substance, such as the lead or ink.

An important object of the invention is to provide a drafting implement having the general construction of a compass, but especially adapted to describe in the same manner as an ordinary compass a curve representing any open or closed figure or outline of non-circular form.

A further object is to provide an implement of the type mentioned that is simple in design, inexpensive to turn out, easy to manipulate, certain in operation, and capable of use by persons of no great skill at any time to attain the required end.

The nature and advantages of the invention are set forth in the ensuing specification, which discloses a preferred embodiment of the device. But this disclosure is explanatory and various changes may be made in details of the combination shown, without deviation from the principle of the improvement, or alteration of its fundamental character, or omission of any of the essential characteristics thereof.

On the drawings:

Figure 1 is a perspective view of a drafting instrument according to this invention;

Figures 2 and 3 show details which are embraced in the invention; and

Figure 4 shows another detail of construction.

The instrument includes a pair of legs 1 and 2, pivotally connected to each other at one extremity, as indicated at 3. The lower end of one of the legs 1 has a foot member 4, pivotally joined thereto by a rivet 5. The foot is made of a flat plate of metal, or other suitable material disposed preferably in the plane of the two legs, and has pointed projections 6 at its opposite ends extending away from the leg 1 carrying it. The other leg 2 has means for carrying a substance for marking the surface of the paper or sheet upon which the instrument is employed, such as the two nibs 7 of a drafting pen to receive ink. Obviously a part carrying a piece of lead can also be utilized. The pen or the lead-bearing member can be of any well known type, detachably secured to the leg 2.

On the leg 1 is a disk or template 8 the peripheral edge of which has the shape of the figure to be described by the leg 1. This disk can be

an oval or ellipse, or have any different shape desired, such as 8a in Figure 3. When this disk is secured in position on the leg 1 with the foot 4 resting on the sheet, and the leg 2 is swung around it, being kept at the same time in continuous contact with the edge of the disk, a curve will be drawn on the sheet reproducing the configuration of the disk 8.

At the center the disk or template has a hub 9, or bearing, in which is a binding screw 10. By means of this bearing the guide element or disk can be shifted along the leg 1, to control the size of the figure described by the leg 2. The farther the disk is from the connection of the legs 1 and 2, the smaller the figure will be.

Attached to the implement adjacent the pivotal connection of the legs 1 and 2 is a retaining element 11, which has the form of a flat bent spring, the ends of which abut and press upon the outer sides of the legs and force the two legs

towards each other. Thus the leg 1 is maintained in engagement with the edge of the guiding element 8. The spring means 11 preferably extends around outside the pivotal connection of the legs.

In Figure 4 the connection of the leg 2 at the top with the other leg 1 is shown in section fully, this connection being such that the leg 1 does not rotate and both points 6 on the pivoted foot 4 are pressed upon the paper or other surface and remain stationary. The top of the leg 1 has a reduced axial projection or journal 1a, upon which is swivelled a coupling member 13, that has a bore 13a receiving the journal 1a. The member 13 has a threaded shouldered projection 13b on which the knob or finger piece 12 is screwed. The leg 2 has a pair of spaced lugs 14 at the top receiving the member 13 between them, and screws 15 secure these lugs to the member 13, the inner ends of these screws being reduced and fitting into a circumferential groove 16 in the journal 1a. The leg 1 has a shoulder at the base of the journal 1a and a reduced projection 17 on which the member 13 seats to form a groove 18 into which the end 11a of the spring 11 is received. This spring has an opening through which the threaded projection 13b extends. With this method of coupling the legs 1 and 2, the knob 12 can be turned to rotate the member 13 on the journal 1a so as to swing the leg 2 around the leg 1, which is held stationary by the points 6 of the foot 4. The spring 11 of course moves with leg 2, the end 11a sliding in the groove 18 above mentioned.

The implement is therefore well calculated to serve all the purposes of the invention, to de-

lineate open or closed figures of any selected shape.

Having described my invention, what I believe to be new is:

1. A drafting implement comprising a pair of legs, one leg having means for carrying a substance for marking a surface, a foot pivotally connected to the other end of the other leg, said foot having pointed projections at its opposite ends extending away from said other leg, and means for pivotally connecting said legs so that one can be turned around the other as an axis, said means comprising a journal on the other leg, a member pivotally mounted on said journal, the one leg having a pair of lugs receiving said member between them, pivot screws uniting said lugs to said member, said journal having a groove to receive the inner ends of said screws, a shouleder projection on said member, a curved spring element having an opening receiving said projection and having pressing engagement at its ends with both said legs, and a knob engaging said projection securing said element thereon.

2. A drafting implement comprising a pair of legs, one leg having means for carrying a substance for marking a surface, a foot pivotally connected to the other end of the other leg, said foot having pointed projections at its opposite ends extending away from said other leg, and means for pivotally connecting said legs so that one can be turned around the other as an axis, said means comprising a journal on the other leg, a member pivotally mounted on said journal,

the one leg having a pair of lugs receiving said member between them, pivot screws uniting said lugs to said member, said journal having a groove to receive the inner ends of said screws, a shouleder projection on said member, a curved spring element having an opening receiving said projection and having pressing engagement at its ends with both said legs, and a knob engaging said projection securing said element thereon, a disk on said other leg above said foot, said disk having the outline of the figure to be reproduced, the disk having a hub-shaped bearing at the center, a binding screw carried by the bearing to retain the disk in adjusted position on said other leg, said element holding the first-named leg in continuous contact with the edge of the disk.
